UNITED STATES PATENT OFFICE.

HENRY F. SHEPHERD, OF PHILADELPHIA, PENNSYLVANIA.

CASE PRINTING AND EMBOSSED MACHINE.

SPECIFICATION forming part of Letters Patent No. 293,797, dated February 19, 1884.

Application filed February 2, 1883. (No model.)

To all whom it may concern:

Be it known that I, HENRY F. SHEPHERD, of the city of Philadelphia, county of Philadelphia and State of Pennsylvania, have invented 55
5 an Improvement in Case Printing and Embossing Machines, of which the following is a specification.

My invention has reference to case printing and embossing machines, but more particularly 10 to that class of machines especially adapted for printing book covers or cases; and it consists in certain improvements in the well-known Ruggles printing-press patented November 10, 1840, by which it is converted into 15 a completely organized case or light embossing machine, as fully set forth in the following specification, and shown in the accompanying drawings, which form part thereof.

The object of my invention is to so construct 20 and arrange the parts of a machine of this class that the strains due to the impression are received by suitable supports in such a manner that no matter where the type or form may be placed on the form-plate there is no possibility 25 of displacement or uneven impression; further, to provide suitable supports for the impression-plate, whereby it may be adjusted vertically without increasing its upward movement, and to provide the receiving-plate with 30 adjustable guides wherewith to insure proper registration of the book-cases placed thereon.

In the drawings, Figure 1 is a sectional side elevation of a machine embodying my improvements, taken on line $x-x$ of Fig. 2. Fig. 2 is a 35 front sectional elevation of same on line $y-y$ of Fig. 1. Fig. 3 is a plan view of the receiving-plate, and shows the guide or registering devices; and Fig. 4 is a cross-section of the registering device on line $z-z$ of Fig. 3.

40 A is the frame of the machine, and is provided at the top with horizontal guideways A' , in which carriage B slides, the latter carrying loosely supported thereon the receiving-plate C, which is prevented from slipping backward 45 by a rib or bar, b. The carriage B carries on its other end one or more inking-rollers, B', adapted to vertical movement. This carriage B is reciprocated by an arm, D, connected thereto at the top by a link, d, and secured to 50 a rock-shaft, D', carried in the frame A, and actuated by an arm, D'', carrying a roller, d'', which works in cam-groove e' in the face of

cam-wheel e, which is driven by a spur-wheel, E, and a pinion, E', on a shaft, E'', the latter being rotated by band-wheels E', and steadied 55 by a fly-wheel, F.

Secured to the frame A on each side, and to the rear of the receiving-plate, are four heavy vertical bolts, G, provided on their tops with nuts g and washers g'. The form-plate H is 60 pivoted at h to the frame A or an extension therefrom, and is supported on the other end by pins or lugs h', so as to lie horizontally between the four bolts G and sufficiently high that when form H' is glued or otherwise secured to the under side thereof it shall be inked 65 by the passing rollers B'. This former-plate is re-enforced on the upper side with heavy hubs h'' and ribs h'', to prevent any bending or springing thereof, and is clamped down in position by housings I, two in number, which extend across the upper face of the hubs of said plate and fit around the bolts G by slots i under nuts g. Immediately below said former-plate is the impression-plate J, which is guided 70 by two downwardly-extending guide-rods, J', which work through holes j in the frame A or extensions therefrom. The bottom of this plate is hinged to the arm K, by which it is actuated, the said arm having its bottom o notched at k, so as to catch upon a pin or lug, L, carried by a hub, M, made fast to a shaft, N. The shaft revolves in bearings n, which may be open at the top, and has secured to it the gear-wheel E and cam-wheel e. The arm 85 K is caused to swing out of reach of the pin L by strap or chain O, which passes over a guide, O', and carries a weight, O'', and may be pulled into operating position by a strap, P, having one end secured to the periphery of wheel P', 90 secured to a shaft rotated by handle p. The impression-plate J is provided on the bottom with stop-pins S, which rest upon the lugs T of frame A, and by which the downward movement of the plate J may be reduced by the interposition of metal pieces t or by increasing 95 the length of said pins, and also relieves all wear from the under side of said plate.

Q is an ink-carrying roller, to ink the inking-rollers B'. The receiving-plate C is provided with an L-shaped guide, R, which is T-slotted, as at r, the longer leg having a loose re-enforcing slide, r', to prevent springing of said long slotted leg. There are three or more 100

additional slide-blocks, r^2 , to which are adjustably pivoted by screws r^3 the registering-arms r^4 , having slots r^5 . The guide R is secured to the plate C by screws R', and may be set to or from the center of the plate; but by the use of arms r^4 and the double housings I this is not necessary, as the pressure given to the impression is equal over the entire surface of the receiving-plate. The operation is as follows: The book case or cover V being placed in position upon the receiving-plate C and brought to the proper register, the handle p is pulled, which throws the arm K into position to be caught by the pin L. Prior thereto, however, the cam-groove e' causes the arm D to be moved forward, causing the carriage and its plate C to move to a position immediately below the form-plate H, where it comes to rest, and during said period of rest the inking-rollers take fresh ink, and the arm K raises the impression-plate J and the receiving-plate C with its case or cover, causing the latter to be pressed

against the form or type H', which is held immovable by the heavy double housings I I. The said plates with the printed or embossed cover then descend, the impression-plate resting on its stop-pins. As soon as the arm K is freed again, the weight O² causes its end to be drawn over to the other side and in position for another impression. The carriage is then moved back and a new case or cover placed upon the plate C, the printed one having been removed.

Having now described my invention, what I claim as new, and desire to secure by Letters Patent, is—

The combination of the impression-plate, its guide-pins, guide-lugs, and stop-pins, substantially as and for the purpose specified.

In testimony of which invention I hereunto set my hand.

HENRY F. SHEPHERD.
